UNITED STATES PATENT OFFICE.

JOHN COTTER PELTON, OF NEW YORK, N. Y., ASSIGNOR TO THE PELTON FIREPROOF CONSTRUCTION COMPANY, OF SAME PLACE.

BUILDING CONSTRUCTION.

SPECIFICATION forming part of Letters Patent No. 663,239, dated December 4, 1900.

Application filed June 1, 1900. Serial No. 18,716. (No model.)

To all whom it may concern:

Be it known that I, JOHN COTTER PELTON, a citizen of the United States, residing at New York city, New York county, New York, 5 have invented certain new and useful Improvements in Building Construction, of which the following is a full, clear, and exact description.

My invention relates to building construction, and particularly to certain new and useful improvements in partitions for buildings.

Among the main objects of my invention are simplicity, effectiveness, durability, and economy of manufacture. An important feature of improvement is to produce a partition which will resist fire to a very marked degree.

In the drawings, Figure 1 is an illustrative side elevation of a partition embodying my 20 invention, said partition being shown partly in section. Fig. 2 is a relatively-enlarged sectional view of a portion of the partition construction shown in Fig. 1, said section being taken on the line X X of Fig. 3. Fig. 3 is a 25 view of a portion of one of the details of construction. Fig. 4 is a perspective view of another detail of construction.

In the drawings I have not attempted to show the space that each of the partition-blocks occupies relatively to the space between the floor and the ceiling, but have illustrated the floor and the ceiling as comparatively close together with only a few partition-blocks between them. With this 35 understanding A is a floor, and B a ceiling.

C C are partition-strengthening devices, preferably formed of sheet-iron. These devices C C are preferably perforated for the purpose hereinafter described. These partition-strengthening devices C C may be secured at their upper ends to the ceiling and at their lower ends to the floor. The means by which the said partition-strengthening devices C C may be secured to said ceiling 40 and floor may be varied, as desired; but I have found that the same may be very effectively fastened by means of nails or the like, as illustrated in dotted lines in Fig. 1, passed through offset ends of said devices C C. 45 These offset ends may be formed integrally by bending the ends of the devices C C lat-

erally, so as to cause them to rest flatwise against the ceiling and the floor, or they may be formed separately, as seen in Fig. 1, in which the said offsets are in the form of clips 55 D D, attached to said fastening devices by suitable clamping members or clips D'. The devices C C are preferably made of two strips of sheet metal, one folded within the other, as indicated in section, Fig. 2. 60

E E are partition-blocks formed of any suitable material—for example, fire-brick—and the same may be, as indicated in the several views, perforated so as to save unnecessary weight. The strengthening devices C C 65 are spaced apart the width of said partition-blocks E, and in setting up the partition the blocks E are slipped into place between the said strengthening devices C. The edges of said blocks adjacent the strengthening devices C are, as shown in Fig. 2, channeled or otherwise suitably recessed for the purpose hereinafter described. When the lower layer of blocks E E are in place, retaining devices F may be employed to temporarily hold the 70 blocks in position, although when the partition is finished said retaining devices are locked in place and materially add to the strength of the structure. The retaining devices F may be formed of sheet metal, and 75 preferably comprise an intermediate shank portion bearing at one end a clip device F', so shaped as to permit the said clip to be engaged with and slide up and down the strengthening devices C when the partition 80 is being built up. The opposite end of the shank of said retaining devices may be provided with offset hooks F², one or more, which may be, as indicated in Fig. 1, pushed into one of the openings in the partition-blocks, 85 thereby preventing the displacement of the block during the process of building up of the partition. Each successive layer of blocks E that are placed in position may be similarly clamped by like retaining devices. By forming two hooks F² at one end of the shank of the retaining device F and turning one hook upwardly and one downwardly one of said hooks may engage the lower partition-block, 90 while the other hook may engage the next superposed partition-block. When the blocks have been inserted in a sufficient number to 95 100

fill up the space between the floor and the ceiling, (or at any intermediate time,) the builder fills the space between the adjacent upright edges of the blocks (shown in Fig. 2) 5 with any suitable cement G. This cement may be flowed in in a liquid state, so that it will surround the strengthening device C and strike the lips at the perforations in the strengthening device C and be directed by 10 them so as to pass through and become anchored in the perforations therein and also fill up the space between adjacent upright edges of the partition-blocks, thereby forming a secure and a positive key, firmly fastening all of the blocks of the partition in a fixed 15 position and securing them to the devices C. When this cement has become set or hard, it serves not only the useful purpose of a key for the several partition-blocks, but it also 20 adds substantial strength to the device C, which it surrounds. Consequently when the partition is finished it is of the strongest possible character and is practically fire-proof.

25 The simplicity of this construction makes it apparent that it may be very quickly built up and completed.

The various elements entering into the construction may be formed of any suitable material, and the order employed in building the 30 partition may be varied at will.

It is obvious that if the partition-blocks are not perforated or recessed at their upper or lower ends there will be no cavity into which 35 the hooked end of the fastening devices F' may be projected, and consequently in place of forming the hooks upon the extreme end of the shank of said fastening device other hooks could be formed at the edges thereof to 40 embrace the opposite sides of the thing to be engaged. An example of a side hook is shown in the drawings, Fig. 1, said hook being indicated by the reference-letter D². Obviously

such a modification and other modifications may be made without departing from the spirit or scope of the invention disclosed and claimed herein. 45

What I claim is—

1. In a building construction in combination, a plurality of partition-blocks having 50 abutting faces, a groove in each abutting face, said grooves coöperating to form a longitudinal opening, a metal strip located in said opening and having tongues punched out of said strip and standing at an angle thereto to 55 receive a filling material and direct the same through the holes in said strip from which said tongues were punched.

2. In a building construction in combination, a plurality of building-blocks having 60 substantially abutting faces, a groove in each block coöperating to form a longitudinal opening, and a strengthening - piece running through said opening, and a device to retain a block in place including a sheet-metal strip 65 bent to engage said strengthening-strip and having an extension to pass along one of the other edges of one of said blocks and engage the same to hold said block in place.

3. In a building construction in combination, a strengthening device running from floor to ceiling, a plurality of building-blocks, each of said blocks having a groove in its vertical face and so placed that said strengthening device is located in said grooves, and a retaining device formed of sheet metal and bent around said strengthening-strip so as to slidably engage the same, said retaining device having an extended foot to pass under the lower edge of one of said blocks and carrying 75 80 engaging means to engage a plurality of said blocks and hold the same in position.

JOHN COTTER PELTON.
